INTERNAL COMBUSTION ENGINE CONTROL

David Gregg, Caldwell, and Richard Daalder,
Paterson, N. J., assignors to Bendix Aviation
Corporation, South Bend, Ind., a corporation of
Delaware

Application December 21, 1938, Serial No. 247,120

14 Claims. (Cl. 123—119)

This invention relates to supercharged internal combustion engines and more particularly to improvements in control mechanism for controlling the supercharging action.

Prior to the present invention the art included supercharger control systems based upon the concept of employing manual control of the supercharger for only a partial throttle control of the carburetor, so that beyond the point where manual control ceases the control of the carburetor 5 throttle (supercharging action) is entirely and exclusively automatic. The present invention utilizes a different concept, namely, the concept of permitting full-range manual control over and 10 above the automatic control at all times and under all circumstances, including the contingency of complete non-functioning of the automatic control. In this connection a feature of the invention (applicable to either the suction type 15 or the pressure type of supercharger system) is the provision of means for locking out the automatic control elements at the will of the operator, with the manual control continuing to function independently of any movement of said automatic control elements—even during the actual 20 process of locking out said automatic elements. This feature of the invention contrasts with the prior art modes of operation including those heretofore applied to the pressure type as well as 25 to the suction type of superchargers. (In using the term "pressure type" it is understood that we refer to the type wherein the supercharger is driven by engine exhaust gases rather than mechanically, and draws air directly from the atmosphere, rather than from the carburetor.)

With particular reference to the automatic control elements themselves, as distinguished from the complete system, the invention further contemplates use of a pressure actuated servo-40 element including a piston whose operating fluid is supplied to opposite sides of the piston under the control of a valve adapted to be shifted to a predetermined position by manual means (to bring about one phase of the "locking out" above 45 referred to) as well as being shiftable by movement of an expansible hollow element (herein shown as a bellows) whose interior is in direct communication with the intake manifold of the engine and therefore reflects the pressure conditions prevailing therein. A further feature is the 50 provision of manual control of manifold pressure by controlling the degree of resistance offered to expansion of the expansible hollow element, said manual control being herein disclosed as incorporated in the same manual control linkage as

that which governs the locking out of the piston, although (as will appear) it may be separate and distinct therefrom, and operated independently thereof.

These and other objects and features of the invention are pointed out in the following description in terms of the embodiment thereof which is shown in the accompanying drawing. It is to be understood, however, that the drawing is for the purpose of illustration only, and is not 10 designed as a definition of the limits of the invention, reference being had to the appended claims for this purpose.

In interpreting the appended claims, where they refer to a supercharger, they are to be construed as including application of the invention to any known type of supercharger, however driven, and to any type of throttle controlled engine; and where the claims are directed to less than all of the elements of the complete system 15 disclosed, they are intended to cover possible uses 20 of the recited elements in installations which lack 25 the non-recited elements.

In the drawing, reference character 5 designates a diagrammatic showing of the intake 30 manifold of an internal combustion engine whose crank-shaft or other power shaft (not shown) drives a supercharger 6 through suitable mechanical connections of which those shown at 7 and 10' may be considered illustrative. The manifold 35 5 serves to connect carburetor 8 with the combustion spaces (not shown) of the engine, by way of supercharger 6 and supercharger inlet 9; the throttle 10 being pivotally mounted in said inlet 40 passage 9, and shiftable to any position between 45 fully open and fully closed in response to corresponding movement of the linkage leading thereto. This linkage includes a manually shiftable throttle control lever 11 and a bell-crank 12 whose central pivot 13 passes through the end 50 portion 14 of a rod 15 whose opposite end is integrated with a piston 16 constituting the servo-element above referred to.

As shown the servo-piston 16 is slideable in a cylinder 17 having two ports 18 and 19 on opposite sides of said piston, through which ports 55 fluid is caused to flow whenever the correspondingly spaced covering portions 21 and 22, respectively, of the slide valve 23 are not in flow inhibiting relation thereto. The operating fluid 60 may be oil received from the engine oil supply by way of pipe 26 and returnable to the engine oil sump by way of outlet 28 or 29, as the case 65 may be, whenever a shifting of the control valve 23 from its neutral position causes one of said 70

outlets to receive oil discharged from the cylinder 17.

The disclosed embodiment of manifold pressure actuated means acting upon control valve 23 to cause supercharger regulating (throttle shifting) movement of the servo-element 16 will now be described. An arm 31 extends in rigid fashion from one end of valve 23 and connects to a plate 32 interposed between a pair of hollow, flexible-walled cylinders or bellows 33 and 34, the former being sealed under vacuum or under a predetermined pressure—although a vacuum or near vacuum is preferred. Bellows 34, on the other hand, has direct communication with intake manifold 5 by reason of conduit 36 leading thereto, and also contains a tube 37 and spring 38 having one end thereof fastened to the end portion 39 of the tube 37; the opposite end of spring 38 being secured to the end portion or collar 41 of a rod 42 constituting part of the manually operable means 64, 74 and 84 for "locking out" the piston 16, and also constituting a means for varying the tension imposed upon spring 38 and thereby varying the degree of opposition to leftward movement of control valve 23 under the urge of the manifold pressure operating upon the bellows 34 in the direction counter to the pull of spring 38. The initial spring tension depends upon the setting of screw 51 in the threaded bearing or nut constituting the above-described end portion 39 of the tube 37; but from this initial adjustment the tension is variable by manually shifting the manifold pressure selecting linkage 64, 74, 84, 42. The range of movement of this linkage 64 to 42 (as indicated by the arc A—B—C—D in the drawing) thus determines the maximum and minimum limits of manifold pressure obtainable by the automatic means constituted by servo-piston 16; it being understood that the piston 16 can move only in response to a shifting of the control valve 23 in either direction from its central position, and that the action of the control valve 23 is in turn governed by the extent to which spring 38 or the existing manifold pressure may temporarily overpower the other and thus cause a temporary shifting of the valve 23 from said central position.

The "locking out" of the servo-element 16, when desired, is accomplished in either one (or both) of two ways: first, by the establishment of a fluid lock, which involves manually shifting the control valve 23 to a position wherein the piston 16 moves to the innermost position and remains there due to the inability of the valve to reverse while the manual restraint thereon remains effective; and secondly, by the establishment of a mechanical lock in the form of latch 61 movable into position to engage groove 62 in the piston rod whenever manually shifted cam 63 (forming part of manifold pressure selecting linkage 64 to 42) occupies a position adjacent either extreme of its range of movement, said extremes of the cam's movement being so set that one extreme coincides with the fluid lock establishing position of the valve shifting rod 42; the result of such coincident settings being, of course, to make it possible to have both the fluid lock and the mechanical lock effective in such manner that the latter supplements and confirms the former. The manner in which these two locking actions are effected will now be described in greater detail. First, as to the fluid lock, this can not occur until the movement of rod 42 is sufficient to bring the collar 41 thereof into abutting engagement 75 with the end of tube 31. After such abutting

engagement occurs, further movement in the same direction will result in corresponding shifting of the valve 23 (to the position shown in the drawing) due to the rigid connection between valve arm 31 and the plate 32 with which tube 37 is integrated. Such shifting of valve 23 will uncover outlet 18 and will thus remove all oil pressure resistance to movement of piston 16 to its innermost position, under the urge of the oil pressure on the outer side of the piston, into which oil is now being supplied by way of ports 28 and 19; the movement of the piston to its innermost position being further assured by reason of the additional pressure exerted by spring 40 upon the outer side of the piston.

Now, as to the mechanical lock (latch) this does not actually take effect until two actions concur: first, the positioning of controlling cam 63 (manually operated by the pressure selecting means 64) in either of the end zones (A—B or C—D) of its range of movement, the entire range of movement being that indicated by the arc A—D as a whole; and secondly, the completion of the inward stroke of the piston 16, whereby groove 62 of the piston rod arrives in position to receive latch 61 and be held firmly thereby, by reason of the pressure exerted in the locking direction by spring 66. These two actions may, of course, be dissimultaneous; that is, the controlling cam 63 may be in either end zone prior to movement of groove 62 to the latch receiving position; but in such event the latch will bear frictionally upon the adjacent portion 70 of the sliding rod 15 until the groove 62 arrives opposite the latch, whereupon the latter will snap into locking position—assuming that in the meantime the operator has not shifted control cam 63 to an intermediate (B—C) position—and thereby provide positive restraint against movement of the piston 16, over and above the resistance to such movement that is due to the pressure of the oil and the spring 40 upon said piston, in this "fluid lock" position of valve 23. With the piston thus locked the operator may exercise full manual control over the throttle by manipulation of throttle lever 11, as above described.

During periods when there is no lock-out of the rod 15, the throttle may be shifted by either the manual means 11 or by movement of the piston, for—as in the prior art—the bell-crank 5 12 is of the floating type, with both its central pivot 13 and its upper pivot 13a serving alternately as fulcrums about which rotation may occur; the pivot 13 being the fulcrum wherein manual actuation occurs, and the pivot 13a when automatic (piston induced) actuation occurs. In this connection it is to be understood that the levers 11 and 64 are held, frictionally or otherwise, in whatever position they are caused to occupy, and remain in such positions until manually shifted.

What is claimed is:

1. The combination with an internal combustion engine throttle, of fluid pressure actuated means for shifting said throttle, said shifting means including a control valve, a piston, a rod and a lever linkage responsive to changes in the engine's manifold pressure, and said piston being subject to a fluid lock tending to hold it at one end of its stroke, means for swinging said lever about one end of said rod to shift said throttle independently of any change in manifold pressure, and manual means for shifting said control valve to a position establishing said fluid lock.
2. The combination with an internal combustion engine throttle, of fluid pressure actuated

means for shifting said throttle, said shifting means including a control valve, a piston, a rod and a lever linkage responsive to changes in the engine's manifold pressure, and said piston being subject to a fluid lock tending to hold it at one end of its stroke, means for swinging said lever about one end of said rod to shift said throttle independently of any change in manifold pressure, manual means for shifting said control valve to a position establishing said fluid lock, and a second lock for the piston in the form of a latch engageable with said rod, said latch being releasable in response to movement of said manual means out of the fluid lock establishing position.

15 3. The combination with an internal combustion engine having an air and fuel inlet conduit, of a servo-motor to control pressure in said conduit, means responsive to a change in the pressure in said conduit for causing pressure controlling movement of said servo-motor, means including a spring opposing the conduit pressure as a servo-motor actuating means, and a hand-manipulable linkage for varying the amount of opposition exerted by said spring.

20 4. The combination with an internal combustion engine having an air and fuel inlet conduit, of a servo-motor to control pressure in said conduit, means responsive to a change in the pressure in said conduit for causing pressure controlling movement of said servo-motor, means including a spring opposing the conduit pressure as a servo-motor actuating means, a hand-manipulable linkage for varying the amount of opposition exerted by said spring, and a second 25 hand-manipulable linkage for exclusively controlling pressure in said conduit when said first-named linkage is in a predetermined position.

25 5. The combination with an internal combustion engine throttle, of fluid pressure actuated means for shifting said throttle, said shifting means including a piston, a rod and a lever linkage displaceable as a unit by changes in the engine's manifold pressure, means for swinging said lever about one end of said rod to shift said throttle independently of any change in manifold pressure, means for locking said piston, said locking means including a control valve controlling delivery of pressure fluid to said piston, manual means for shifting said control valve to piston locking position, and a second lock for the piston in the form of a latch engageable with said rod, said latch being releasable in response to movement of said manual means out of the position corresponding to piston locking position.

30 55 6. The combination with an internal combustion engine having an air and fuel inlet conduit in which the pressure tends to vary as the altitude varies, of means to control the pressure in said conduit, said means including a piston rod, a piston, and a valve controlling delivery of pressure fluid to said piston for movement of said rod, manual means for shifting said valve, and means engageable with said rod to lock the piston against movement, said locking means being operable in response to a predetermined degree of movement of said manual valve shifting means.

35 7. The combination with an internal combustion engine having an air and fuel inlet conduit in which the pressure tends to vary as the altitude varies, of means to control the pressure in said conduit, said means including a piston rod, a piston, and a valve controlling delivery of pressure fluid to said piston for movement of said

40 rod, fluid pressure responsive means for shifting said valve in one direction, means opposing said fluid pressure responsive means, manual means for increasing the effectiveness of said opposing means, and a latch engaging said piston rod in response to a predetermined degree of movement of said manual means.

45 8. The combination with an internal combustion engine having an air and fuel inlet conduit in which the pressure tends to vary as the altitude varies, of means to control said conduit pressure, said means including a piston having an extension, locking means therefor including a latch engageable with said piston extension, means constantly urging said latch to latching position, and manual means restraining said latch and preventing its movement to latching position so long as said manual means occupies any position within a predetermined zone.

50 9. The combination with an internal combustion engine having an air and fuel inlet conduit in which the pressure tends to vary as the altitude varies, of means to control said conduit pressure, said means including a piston having an extension, locking means therefor including a latch engageable with said piston extension, means constantly urging said latch to latching position, and manual means restraining said latch and preventing its movement to latching position so long as said manual means occupies any position with a predetermined zone located between two additional zones constituting additional parts of the complete range of movement of said manual means.

55 10. The combination with an internal combustion engine having an air and fuel inlet conduit in which the pressure tends to vary as the altitude varies, of means to control said conduit pressure, said means including a piston having an extension, locking means therefor including a latch engageable with said piston extension, means constantly urging said latch to latching position, manual means restraining said latch and preventing its movement to latching position so long as said manual means occupies any position with a predetermined zone, and means on said piston extension for delaying effectiveness of said latch until said piston reaches a predetermined position in its stroke.

60 11. The combination with an internal combustion engine having an air and fuel inlet conduit in which the pressure tends to vary as the altitude varies, of means to control said conduit pressure, said means including a piston having an extension, locking means therefor including a latch engageable with said piston extension, means constantly urging said latch to latching position, manual means restraining said latch and preventing its movement to latching position so long as said manual means occupies any position within a predetermined zone located between two additional zones constituting additional parts of the complete range of movement of said manual means, and means on said piston extension for delaying effectiveness of said latch until said piston reaches a predetermined position in its stroke.

65 12. The combination with an internal combustion engine having an air and fuel inlet conduit in which the pressure tends to vary as the altitude varies, of means to control said conduit pressure, said means including a piston rod, a piston, and a valve controlling delivery of pressure fluid to said piston for movement of said rod, manual means for shifting said valve, means

70 75

engageable with said rod to lock the piston against movement, said locking means being operable in response to a predetermined degree of movement of said manual valve shifting means, and fluid pressure responsive means for shifting said valve independently of any movement of said manual means.

13. The combination with an internal combustion engine having an air and fuel inlet conduit in which the pressure tends to vary as the altitude varies, of means to control said conduit pressure, said means including a piston rod, a piston, and a valve controlling delivery of pressure fluid to said piston for movement of said rod, manual means for shifting said valve, and means engageable with said rod to lock the piston against movement, said locking means being operable when said valve is in a position causing
- 10
- 15

unbalanced fluid pressure on opposite sides of said piston.

14. The combination with an internal combustion engine having an air and fuel inlet conduit in which the pressure tends to vary as the altitude varies, of means to control said conduit pressure, said means including a piston rod, a piston, and a valve controlling delivery of pressure fluid to said piston for movement of said rod, fluid pressure responsive means for shifting 10 said valve in one direction, a spring opposing said fluid pressure responsive means, manual means for increasing the opposing force of said spring, and a latch engaging said piston rod in response to a predetermined degree of movement 15 of said manual means.
